ATTORNEY

UNITED STATES PATENT OFFICE.

MURRAY P. HENDRICKS, OF BENWOOD, WEST VIRGINIA.

SHAVING-BRUSH.

1,194,735.

Specification of Letters Patent. Patented Aug. 15, 1916.

Application filed May 5, 1916. Serial No. 95,670.

To all whom it may concern:

Be it known that I, MURRAY P. HENDRICKS, a citizen of the United States, residing at Benwood, in the county of Marion, State of West Virginia, have invented certain new and useful Improvements in Shaving-Brushes, of which the following is a specification.

This invention relates to shaving brushes and more particularly to a demountable shaving brush which may be assembled in a manner, when not in use, that will cause the brush to take up a minimum of space and confine the bristles of the brush in a casing whereby they will be protected from dust or other unsanitary elements.

As a further object, the invention contemplates the provision of a device of this character which will catch the water and lather at its flows downwardly from the bristles when the brush is being used, thereby preventing the hand of the person holding the brush while applying the lather to his face, from becoming wet.

The invention further aims to provide a receiving cup of a diameter great enough to catch the water from the bristles and also with a container which is formed in the handle whereby the water or lather may pass from the cup into the handle or container thus providing for the reception of a large quantity of water.

The above and additional objects are accomplished by such means as are illustrated in the preferred embodiment and in the accompanying drawings, wherein like characters denote like or corresponding parts throughout the several views, in which:—

Figure 1 is a side elevation. Fig. 2 is a vertical longitudinal section. Fig. 3 is a vertical section showing the brush in collapsed position. Fig. 4 is a plan view of the brush as it is shown in Fig. 3.

The handle 1 of the brush is formed of a cylindrical hollow member 2 provided with an end wall 3 which closes one end of the handle thus providing the container 4 for the reception of liquid or lather as it flows from the bristles. One end of the cylindrical member 2 is provided with a tapered portion 5 which increases in diameter to provide the enlarged sleeve 6 the purpose of which will be presently described. A receiving cup 7 is integrally formed with the sleeve 6 and is of a diameter larger than the sleeve 6. A cylindrical interior sleeve 8 is

adapted to snugly fit within the sleeve 6 and one end is provided with the usual cement or hard rubber 9 in which the ends of the bristles 10 are embedded. The circular disk 11 is arranged within the interior sleeve 8 and rests upon the end of the securing material 9. Formed in the interior sleeve 8 is a plurality of apertures 12 which are provided to establish communication between the cup 7 and the container 4 and from this construction it will be observed that while the person using the brush is applying the water or lather to his face, the water from the bristles which will run downwardly will be caught by the cup 7 and pass into the container 4 where it will be held until the brush is inverted to dispense the water.

The diameter of the interior sleeve 8 is the same throughout its length so that either end of the sleeve will snugly fit within the sleeve 6 and in this manner the bristles 10 may be thrust into the container 4 as shown by Fig. 3 of the drawing thereby rendering the bristles clean and sanitary and adapted to be packed in a minimum space.

In reduction to practice I have found that the form of my invention illustrated in the drawings and referred to in the above description, as the preferred embodiment, is the most efficient and practicable; yet realizing that the conditions concurrent with the adoption of my device will necessarily vary, I desire to emphasize the fact that various minor changes in the details of construction, proportion and arrangement of parts may be resorted to, when required, without sacrificing any of the advantages of my invention, as defined in the appended claims.

I claim:

1. A shaving brush comprising a tubular handle closed at one end to provide a container, the opposite end of said handle being outwardly tapered, the tapered portion terminating in an exterior sleeve of cylindrical formation and of a diameter greater than the diameter of said container, a cup carried by said sleeve, said cup being integrally formed with the sleeve and formed by enlarging the extreme end of the sleeve, an interior cylindrical sleeve fitted within said exterior sleeve and extending outwardly beyond the end of said cup and provided with a plurality of apertures for establishing communication between the interior of said container and the said cup,

the said interior sleeve adapted to be inverted whereby either end may be fitted within said exterior sleeve, a brush element carried by one end of said interior sleeve, 5 and a disk mounted in said interior sleeve and disposed between the said openings and the interior ends of the bristles comprising said brush element, whereby the liquid passing from said cup into the container 10 will be prevented from contacting with the end of said brush element.

2. A shaving brush comprising a tubular container provided with a tapered portion at one end, a sleeve carried by the tapered portion and having a cup formed at its extreme end, an interior sleeve mounted within said exterior sleeve beyond the outer end 15

of said cup, a brush element carried by one end of said interior sleeve, said interior sleeve having a fastening means for the end of 20 said brush element, a disk mounted within the said interior sleeve and bearing against said securing means, the diameter of said interior sleeve being equal throughout its length whereby either end of said sleeve 25 may be releasably secured in said exterior sleeve.

In testimony whereof I affix my signature in presence of two witnesses.

MURRAY P. HENDRICKS.
